(57) CLAIM

The ornamental design for a golf club head, as shown and described.

DESCRIPTION

FIG. 1 is a bottom perspective view of a golf club head showing my new design;

FIG. 2 is a bottom view thereof;

FIG. 3 is a toe end view thereof; and,

FIG. 4 is an enlarged view of FIG. 2 that shows the claimed design.
